US00D559223S

(12) **United States Design Patent** (10) **Patent No.:** **US D559,223 S**
Kim et al. (45) **Date of Patent:** **** Jan. 8, 2008**

(54) **PORTABLE TELEPHONE**

(75) Inventors: **Jin-Nam Kim**, Seoul (KR); **Hyun-Seop Kim**, Seoul (KR); **Chang-Hwan Hwang**, Seoul (KR)

(73) Assignee: **Samsung Electronics Co., Ltd.**, Kyunggi-do (KR)

(**) Term: **14 Years**

(21) Appl. No.: **29/286,176**

(22) Filed: **Apr. 26, 2007**

(51) **LOC (8) Cl.** **14-03**

(52) **U.S. Cl.** **D14/138**

(58) **Field of Classification Search** D14/137-138, D14/147-148, 156, 218, 247-248, 341-347, D14/496; D16/208; D21/329, 331, 333, D21/517; 348/14.01-14.02; 361/814; 379/ 433.01-433.13; 455/90.3, 556.1-556.2, 455/566, 575.1, 575.3, 575.4
